[57] CLAIM

The ornamental design for a yard stand for hanging baskets, as shown and described.

DESCRIPTION

FIG. 1 is a front elevation view of a yard stand for hanging baskets showing my new design, the rear elevational view being identical thereto;

FIG. 2 is a right side elevational view thereof, the left side elevational view being identical thereto;

FIG. 3 is a top plan view thereof, at a slightly enlarged scale compared to FIG. 1 and FIG. 2; and,

FIG. 4 is a bottom plan view thereof, at the same scale as FIG. 3.

The bracketed break shown on the post in FIGS. 1 and 2 indicates indeterminate length.
